UNITED STATES PATENT OFFICE.

JACOB R. MERTES, OF MILWAUKEE, WISCONSIN.

MATTRESS HANDLE.

Application filed April 27, 1925. Serial No. 26,087.

To all whom it may concern:

Be it known that I, JACOB R. MERTES, a citizen of the United States, and resident of Milwaukee, in the county of Milwaukee and

6 State of Wisconsin, have invented certain new and useful Improvements in Mattress Handles; and I do hereby declare that the following is a full, clear, and exact description thereof.

10 This invention relates to mattress construction and is particularly directed to handles for mattresses.

In handling mattresses, it is well known that difficulty is experienced in securing a 15 firm grip on the mattress and also when it is desired to sun or air the mattress, it is necessary to lay the mattress over a support and to occasionally turn the mattress to present both sides to the sunlight.

20 This invention is designed to overcome the above noted defects, and objects of the invention are to provide handles for a mattress which are so constructed that they may be most easily gripped by the operator in 25 turning the mattress or moving it, which are adapted to be looped over a line and to thus support the mattress and expose both sides thereof.

30 Further objects are to provide handles for a mattress which are reenforced at their points of union with the mattress in a novel and highly effective manner, and to provide handles which have a detachable portion to thus permit their ready looping over a supporting line without requiring the threading of the line through the handles.

An embodiment of the invention is shown in the accompanying drawings, in which:—

35 Figure 1 is a perspective view of a mattress equipped with the handles.

Figure 2 is an enlarged sectional view showing one of the handles.

Figure 3 is a face view of the structure shown in Figure 2, with parts broken away.

40 Figure 4 is an enlarged top view of the upper reenforcing member, with a part of the covering therefor broken away.

45 Referring in detail to the drawings, it will be seen that the mattress 1 is provided with a plurality of handles along one edge thereof. These handles each comprise a fixed portion 2 and a portion 3 which is secured at one end to the portion 2 and adapted for detachable attachment thereto at the 55 other end.

These handles are of identical construc-

tion and one only need, therefore, be described in detail.

Referring particularly to Figures 2, 3 and 4, it will be seen that an upper and a lower angle iron or metal reenforcing member, indicated at 4 and 5, respectively, are provided. These reenforcing members are enclosed by a flexible strap like sheath which forms the portions 2 and 3. This sheath is folded about the angle irons and stitching extends through the sheath and through apertures 6 formed in such angle irons, as clearly shown in these figures.

It is to be noted further that this construction provides a double thickness for the portions 2 and 3 and a very substantial reenforce at the upper and lower edges of the mattress. If desired, the portion 3 may be made of a separate piece from the portion 2 and attached, as indicated at 7, in Figure 2, beneath an overlapping portion of the member 2.

It is to be noted further that the upper angle iron 4 has a bifurcated upper portion 80 to provide a pair of legs 8 (see Fig. 4). Between these legs a hook 9 is pivotally mounted upon a pintle pin 10, such pintle pin being secured by passing it through downwardly struck portions of the feet 8. The outer end of the member 3 is reenforced by means of a metal plate 11, and a line of stitching 12 is passed across the member 3 adjacent such plate to hold it rigidly in position. This plate, together with the 90 strap 3, is provided with an aperture 13 adapted to be engaged by the hook 9 when the handle is to be used.

In using the device it is merely necessary to rock the members 3 upwardly and to pass the hooks 9 through the apertures 13. This forms a plurality of flexible loop-like handles by means of which the mattress may be most readily handled.

Further, it is to be noted that when it is desired to sun or air the mattress, the members 3 are passed over the line or other support and are then engaged by the hooks 9, thus securely suspending the mattress from the line.

It is to be noted further that the angle irons 4 and 5 form a very secure reenforce for the attached portions of the handles and prevent inadvertent tearing of the handles from the mattress.

110 Although the invention has been described in considerable detail, it is to be understood

2
that the invention may be variously embodied and is, therefore, to be limited only as claimed.

I claim:

- 5 A strap-like handle for a mattress comprising an enclosing sheath, angle irons carried within said sheath and adapted for positioning adjacent the upper and lower corners of the mattress, said angle irons being
10 apertured for the reception of securing means passed through said sheath, angle irons and mattress, a hook carried by one of

said angle irons, said sheath having an extension projecting from adjacent the other angle iron, and a reenforcing plate positioned in the outer end of said extension, said extension and plate being apertured for the reception of said hook.

In testimony that I claim the foregoing I have hereunto set my hand at Milwaukee, in ¹⁵ the county of Milwaukee and State of Wisconsin.

JACOB R. MERTES.
